UNITED STATES PATENT OFFICE.

ANDREW J. BRADLEY, OF NEW YORK, N. Y.

MACHINE FOR PRINTING ON SHOE-LININGS AND THE LIKE.

No. 920,531.

Specification of Letters Patent.

Patented May 4, 1909.

Application filed June 10, 1903. Serial No. 437,618.

To all whom it may concern:

Be it known that I, ANDREW J. BRADLEY, a citizen of the United States, and a resident of the city of New York, county of New York, 5 and State of New York, have invented a new and useful Improvement in Machines for Printing on Shoe-Linings and the Like, of which the following is a specification.

My invention relates to machines for printing on shoe linings, collars, linens and other articles, and has for its principal objects to facilitate the adjustment of the type carrying members; to secure steadiness of type carrying members during the act of printing; 10 to facilitate the positioning of the printed matter; to facilitate the restoring of the parts to normal position; to provide for the proper inking of the type; and to secure other advantages hereinafter appearing.

It consists principally in yieldingly securing the printing members upon a movable supporting device common to them all and providing means for locking the respective printing devices, whereby the several printing devices may be readily adjusted in proper 15 relation to each other.

It also consists in the parts and in the arrangements and combinations of parts hereinafter described and claimed.

In the accompanying drawings, which form part of this specification, and wherein like symbols refer to like parts wherever they occur, Figure 1 is a side elevation of a printing machine embodying my invention with 20 the parts shown at the moment of printing; Fig. 2 is a detail view of a device for locking a printing wheel in its adjusted position; Fig. 3 is a vertical cross section of my machine, with the inking mechanism, the tympan 25 frame and other actuating mechanism shown in elevation; Fig. 4 is an isometric sectional view of the inking pad and means for supporting it; Fig. 5 is a plan view of my machine; Fig. 6 is a sectional detail view of the 30 type wheel axle with a number of type wheels thereon; Fig. 7 is a detail view of a portion of a type wheel mounted on a common axle, a portion of a type wheel being shown in section to illustrate its locking pin 35 in engagement with the groove of the axle; Fig. 8 is a plan view of the base of the machine, the tympan frame and the means for actuating said tympan frame; Fig. 9 is a vertical cross section through the base portion 40 of the machine and the tympan frame, on the line 9—9 of Fig. 8 but with the rock lever and

the corner of the tympan frame shown in elevation.

The frame of my machine comprises a substantially rectangular base 1 having forwardly and rearwardly extending feet, and vertical side members 2, which side members are connected by horizontal cross members or braces 3. Rotatably mounted on said side members is a main shaft 4, upon which 40 is fixed a drum or axle 5 which has a longitudinal depression, preferably a V-shaped groove, in its periphery. Mounted upon said frame or axle 5 is a series of type wheels 6 or other suitable type carrying members. 45 The periphery of each wheel is divided into a number of equal surfaces separated by intervening V-shaped indentations. Each of these surfaces (except one, which is left blank) is provided with a type or printing character. 50 Preferably, each wheel is the counterpart of its fellows. Each of these type wheels has a radial hole therein, in which is mounted a pin 7 whose inner end is made of conical shape to adapt it to fit in the V-shaped 55 groove of the drum or axle. Back of said pin is a coiled spring 8 which bears at one end against said pin and bears at its other end against a screw-threaded plug 9 which cooperates with an internal screw-thread provided therefor in the outer end of the hole in 60 said wheel. By turning the screw plug, the pressure on the pin may be varied at pleasure and the force required to disengage said pin from its counterpart groove is varied accordingly. 65

In the normal position of the parts, the locking pin on each of the type wheels is in engagement with said V-shaped groove in the axle. When the axle or drum is rotated, all 70 the type wheels are normally turned therewith. When the drum has been turned to bring a particular type wheel into a desired position, that particular wheel is locked in that position, and so long as said wheel is 75 locked, the movement of the drum or axle has no effect thereon. The locking device comprises a lever 10 for each type wheel. These levers are fulcrumed on a rod or bar 11 mounted on the framework parallel with the 80 drum or axle. Each lever has a tooth or pawl 12 on the edge thereof of a size and shape to fit in the indentations in the periphery of the corresponding type wheel and thus serve to position the wheel accurately as well as to 85 lock it. The end of the lever is arcuate and has two notches or indentations therein ar- 90

ranged to coöperate with a spring-actuated pin 13 provided therefor on the frame. One of said notches is in position to interlock with said pin when the corresponding pawl 12 engages an indentation in the periphery of the type wheel; and the other notch in said lever is in position to engage said pin when the pawl is tilted clear of the type wheel. The end of each lever is provided with a handle or finger grip 14 for manipulating it to engage with the type wheel. Each lever also has a depending projection 15 which is offset and extends inwardly beyond the periphery of its type wheel. On the face of each type wheel is a pin or stud 16 which is close enough to the periphery thereof to bear against said projection, whereby said projection constitutes a stop for limiting the rotation of the type wheels. Mounted in the side members of the frame parallel with the fulcrum of the locking levers adjacent to the projections thereon is a bar or rod 17, whose end is provided with a crank arm 18 equipped with a handle 19 for manipulating it. This bar is preferably of semicircular section and is so positioned that when the locking levers are in engagement with their respective type wheels, their edges bear against the flat surface of said bar. When the bar is rotated by means of its hand crank, it acts as a cam working against said projections to turn said levers out of engagement with their respective wheels and restore them to their normal positions.

35 Mounted on one of the side members of the frame is a stub shaft 20; on which is mounted a curved rack or sector 21 whose teeth mesh with the teeth of a pinion 22 fixed on the drum or axle 5. The outer end of this stub shaft is provided with a crank arm 23 having a handle 24 thereon, and with an outwardly extending portion 25 which is turned inwardly to overlap the margin of the side member of the frame and constitute a pointer. The front and upper portion of this side member are made in the form of a circular arc upon which is mounted a strip of metal 26 bearing characters corresponding to those of the several type wheels. These characters are arranged in the inverse order of those on the printing wheels and are so spaced and positioned that the pointer registers with each character as the like character on a type wheel fixed to the axle is in printing position.

60 The operation of setting up an item is as follows: Normally all the type wheels are locked to the axle by means of their spring pins engaging in the groove of the axle. Suppose the item to be set up is A 425. The hand crank is turned until the pointer registers with the number 5 on the indicator, whereupon the locking lever of the first type wheel to the right is manipulated to move its pawl into engagement with the indentation

of the type wheel. Thereupon, the hand crank is again turned until the pointer registers with the character 2 of the indicator, whereupon the locking lever of the second type wheel is manipulated to lock said wheel. Then the hand lever is again moved until the pointer registers with the character 4, whereupon the locking lever of the third wheel is manipulated to lock said wheel. Then the hand crank is again turned until the pointer registers with the character A of the indicator, whereupon the locking lever of the fifth type wheel is manipulated to lock said fifth wheel. The hand crank is then turned back to normal position. During these operations, the wheels that are not locked move with the axle, whereas those that are locked remain locked until intentionally disengaged. As the fourth wheel was not locked, a space is left between the character A and the number 425 and the item can be printed as often as desired without resetting the machine. So, too, the wheels may be locked in any order that may be desired. When it is desired to restore the machine to normal position, the hand crank 18 is turned, whereupon the bar 17 bears against the projections on the locking levers to disengage said locking levers from the indentations of the type wheel, whereupon the hand crank 23 is turned until the studs or pins on the respective wheels bear against the projections on the several locking levers, in which position the spring pins on the wheels engage the longitudinal groove of the axle. The ink supply is preferably an absorbent pad 27 removably supported by the side members of the frame. This absorbent pad is preferably mounted on the underside of a partially cylindrical plate 28 of resilient metal arranged concentric with the type wheels. One end of said plate is turned down and fixed to a flat bar 29 whose ends fit in slotted studs 30 provided therefor on the end members of the frame. As illustrated in Fig. 4, one or both of said studs has its bottom open and is provided with a spring member 31 which is adapted to close said bottom and constitute a support for said bar. This spring member is provided with a finger piece 32 whereby it may be pulled laterally out of alignment with said slot and thus permit the mounting or dismounting of the bar which supports the ink pad.

65 Pivots mounted on the shaft 4 beyond the type wheels is a pair of arms 33 which are connected or framed together by a cross member 34. The ends of these arms are slotted longitudinally to receive the spindles of an ink roller 35. In order to allow movement of said ink roller longitudinally of said arms, its spindles are fitted into the eyes of eyebolts 36 which extend through perforated lugs 37 provided therefor on said arms. The inner ends of these eyebolts are screw-

threaded and provided with nuts 38. Around the inner portions of these eyebolts are coiled springs 39 whose outer ends bear against the perforated lugs and whose inner 5 ends bear against the adjusting nuts, whereby the pressure on the inking roller against the type wheel may be varied at pleasure and whereby the type wheel is permitted to move outwardly and inwardly to a limited 10 extent.

The ink roller is provided at its ends with rollers or disks 40 which travel on tracks 41 provided therefor on the frame of the machine. These tracks are arranged to keep 15 the ink roller clear of the type of the respective type wheels except for the space of a single type, which space corresponds to the printing position. At this point, there is a sufficient depression 42 on the track to permit 20 the ink roller to bear against the type. The portion of the track close to the inking pad is arranged to cause the roller to travel over said pad. In the normal position of the parts the ink roller is far removed from 25 the inking pad but is brought into operative relation therewith by the manipulation of the printing lever hereinafter mentioned.

Pivottally mounted on the base portion of the main frame is a substantially rectangular 30 tympan frame 43. On the upper side of the outer marginal portion of this tympan frame is mounted a tympan 44 whose sides are inclined or pyramidal. On the upper side of the tympan frame are perforated lugs 35 45 in which is mounted a rod or pintle 46. Pivottally mounted on this rod is a clamping plate or member 47 which is normally held downwardly by springs 48 coiled around said rod and bearing against said plate. The 40 marginal portion of said pivotal plate extends beyond the tympan and is provided in its marginal portion with a slot 49 in position to register with said tympan and of such size that its edges bear against the inclined 45 sides of said tympan. Mounted on the tympan frame is a rock lever 50 provided with a knob or handle 51 for manipulating it. The short arm 52 of this lever is positioned under the clamping plate and operates 50 as a cam to raise said clamping plate against the force of its springs when the longer arm is manipulated.

The shaft 53 to which the tympan frame is fixed is provided with a crank handle 54 at 55 its end for manipulating it. The parts are so designed that when the tympan frame is lifted, it will bear radially against the type that are in printing position; that is, the axis of the shaft 53 of the tympan frame is in 60 or adjacent to a plane that is tangent to the type wheels at the point of printing.

As stated above, the frame or arms 33 which support the inking roller are pivotally mounted on the main shaft. This frame has 65 rock arms 55 fixed thereto, and the rock

arms are connected by pivotal links 56 to the respective ends of the tympan frame. By this arrangement, the movement of the tympan frame is transmitted through said links and the rock arms to swing the ink 70 roller as hereinabove described. In order to secure the desired movement of the ink roller relative to the tympan frame, the links are preferably bent as illustrated in the drawing.

In operation, the tympan frame is normally in the horizontal position with the tympan projecting through the slot of the clamping member. In order to position the shoe lining or other article to be printed, the 80 clamping member is raised by manipulation of the rock lever, whereupon the article is positioned on the tympan, the rock lever is then restored to its position, whereupon the spring of the clamping member forces 85 said member downwardly stretching the article over the tympan and binding it firmly against the pyramidal sides thereof. The hand crank is then manipulated to bring the tympan into contact with the type wheels, 90 during which operation the ink roller is moved across the type that are in printing position and over the inking pad. Unless the ink roller has been in service shortly prior to this operation, it will be necessary 95 to repeat the operation in order to ink the type well. Upon the return stroke of the tympan frame, the ink roller is restored to its normal position and in returning again inks the type wheel.

Obviously my machine admits of considerable modification without departing from my invention, and therefore, I do not wish to be limited to the specific construction shown and described.

What I claim is:

1. A printing machine comprising a frame, an adjustable type carrying member mounted thereon and having a series of indentations on its periphery, means for adjusting 110 said type carrying member, and means for retaining said type carrying member in adjustment, said retaining means comprising a pawl pivotally mounted on said frame, said pawl being normally in inoperative relation 115 to said type carrying member and arranged to be brought into engagement with said type carrying member, means for holding said pawl either in or away from engagement with said type carrying member, and 120 means for manipulating said pawl.

2. A printing machine comprising a frame, an adjustable type carrying member mounted thereon and having a series of indentations in its periphery, means for adjusting 125 said type carrying member, and means for retaining said type carrying member in adjustment, said retaining means comprising a pawl pivotally mounted on said frame and arranged to be brought into engagement with 130

said type carrying member, a spring pressed pin mounted on said frame and arranged to hold said pawl either in or away from engagement with said type carrying member, 5 and means for manipulating said pawl.

3. A printing machine comprising a frame, an adjustable type carrying member mounted thereon and having a series of indentations on its periphery, means for adjusting 10 said type carrying member and means for retaining said type carrying member in adjustment, said adjusting means comprising an axle having a longitudinal groove thereon, a spring pressed pin mounted on said type carrying member and arranged to yieldingly engage said groove, a stop for limiting the movement of said type carrying member, and means for actuating said axle, said retaining means comprising a pawl pivotally 15 mounted on said frame and arranged to be brought into engagement with said type carrying member, means for holding said pawl either in or away from engagement with said type carrying member, and means 20 for manipulating said pawl.

4. A printing machine comprising a frame, independently adjustable type carrying wheels mounted thereon each having a series of indentations in its periphery, means 30 for adjusting said wheels, and means for retaining said wheels in adjustment, said adjusting means comprising an axle having a longitudinal groove therein, a spring pressed pin mounted on each of said wheels and arranged to yieldingly engage said groove, a stop for limiting the movement of said wheels and means for actuating said axle, said retaining means comprising a series of pawls pivotally mounted on said frame and arranged to be brought into engagement with the respective wheels, a spring pressed pin for each pawl mounted on said frame and arranged to hold said pawl either in or away from engagement with the corresponding 40 wheel, and means for manipulating said pawl.

5. A printing machine comprising a frame, a series of rotatable type wheels mounted thereon, means for adjusting said type 50 wheels either singly or together, means for retaining said type carrying members in adjustment, said means being normally in inoperative relation to said wheels, respectively, stops for limiting the movement of said type carrying members, respectively, and means 55 for actuating said axle, said adjusting means comprising an axle having a longitudinal groove therein, spring pressed pins mounted on said type carrying members, respectively, and arranged to yieldingly engage said groove.

6. A printing machine comprising a frame, a series of rotatable type wheels mounted thereon, means for adjusting said type 60 wheels either singly or together, means for

retaining said type carrying members in adjustment, stops for limiting the movement of said type carrying members, respectively, said adjusting means comprising an axle having a longitudinal groove therein, spring 70 pressed pins mounted on said type carrying members, respectively, and arranged to yieldingly engage said groove, and means for actuating said axle said actuating means comprising intermeshing toothed members 75 and a hand lever.

7. A printing machine comprising a frame, a series of adjustable type wheels mounted thereon and each having on its periphery a series of indentations, means for adjusting 80 said type carrying members and means for retaining said type carrying members in adjustment, said retaining means comprising a series of pawls pivotally mounted on said frame and arranged to be brought into engagement with said type wheels, respectively, but being normally in inoperative position, means for holding said pawls either in or away from engagement with said type 85 wheels, respectively, and means for manipulating 90 said pawls.

8. A printing machine comprising a frame, a series of adjustable type wheels mounted thereon and each having on its periphery a series of indentations, means for adjusting 95 said type carrying members and means for retaining said type carrying members in adjustment, said retaining means comprising a series of pawls pivotally mounted on said frame and arranged to be brought into engagement with said type wheels, respectively, means for holding said pawls either in or away from engagement with said type wheels, respectively, and means for manipulating 100 said pawls, said manipulating means comprising a restoring cam mounted on said frame in position to raise by one movement all of said pawls away from engagement with said type carrying members, respectively, and means for actuating said restoring cam. 110

9. A printing machine comprising a frame, a rotatably mounted axle thereon, a series of type wheels rotatably mounted on said axle and individually yieldingly secured thereto, means for turning said axle, means for engaging and locking said type wheels individually wherever adjusted, said locking means being normally in inoperative relation to said wheels, and means for indicating the angular 115 adjustment of said axle and means common to all of said locking means for disengaging them from their respective type wheels. 120

10. In a printing machine, a main frame, a tympan frame pivotally mounted on said main frame and comprising a base portion having 125 a raised tympan with pyramidal sides, a spring pressed work-holding member pivotally mounted on said base portion and having a slot whose edges are adapted to bear against the sides of said tympan, and a man- 130

ually operable rock shaft arranged to oscillate said work-holding member.

11. A printing machine comprising a main frame, an adjustable type carrying member 5 mounted therein, means for adjusting said type carrying member, means for retaining said type carrying member in adjustment, a tympan frame movably mounted on said main frame, a tympan mounted on said tympan 10 frame, a spring actuated grip frame pivotally mounted on said tympan frame and having a slot therein adapted to fit over said tympan, means for raising said grip frame away from contact with said tympan.

15 12. A printing machine comprising a main frame, an adjustable type carrying member mounted thereon, means for adjusting said type carrying member, means for retaining said type carrying member in adjustment, a 20 tympan frame movably mounted on said main frame, a tympan mounted on said tympan frame, a spring actuated grip frame pivotally mounted on said tympan frame and having a slot adapted to fit over said 25 tympan, means for raising said grip frame away from contact with said tympan, said raising means comprising a rock shaft having a cam mounted thereon, and a hand lever for manipulating said rock shaft, and means 30 for moving said tympan frame into operative contact with said type carrying member.

13. A printing machine comprising a main frame, an adjustable type carrying member mounted thereon and an ink roller, brackets 35 mounted on said main frame and having slots therein respectively, spring catches fastened to said brackets respectively and arranged to close said slots, a bar mounted in said slots and normally held in position by 40 said spring catches, an ink pad frame mounted on said bar and having thereon an ink pad.

14. In a printing machine, a main frame, a series of type wheels independently adjustably mounted thereon, an ink roller for inking 45 said type wheels, an inking pad for said roller, and means for supporting said inking pad, said means comprising a curved resilient plate arranged substantially concentric with said wheels.

15. In a printing machine, a main frame, a 50 series of type wheels independently adjustably mounted thereon, an ink roller for inking said type wheels, an inking pad for said roller, and means for supporting said inking pad, said means comprising slotted lugs on 55 the frame, a cross bar mounted in said lugs and a member mounted on said cross bar and having a pad mounted thereon, and a removable member for closing one side of the slot for locking said bar therein. 60

16. In a printing machine, a main frame, a series of type wheels independently adjustably mounted thereon, an ink roller for inking 65 said type wheels, an inking pad for said roller, and means for supporting said inking pad, said means comprising a cross bar mounted in slots provided therefor on the main frame and manually operable spring members adapted to lock said bar in said slot. 70

17. A printing machine comprising a rotatable axle, a plurality of type wheels independently rotatable on said axle and normally held in yielding engagement therewith, means for positively locking said 75 wheels individually and manually operable means for resetting all of said locking means in normal position said locking means being normally disengaged from said wheels.

18. A printing machine comprising a rotatable axle, a plurality of type wheels independently rotatable on said axle and normally held in yielding engagement therewith, a plurality of locking levers arranged to lock 80 said wheels individually, and means for resetting said locking levers, said resetting means comprising a manually operable shaft having an eccentric portion arranged to bear 85 against said locking levers.

In testimony whereof, I have signed my 90 name to this specification in the presence of two subscribing witnesses this 8th day of June, 1908, at New York, New York.

ANDREW J. BRADLEY.
